REFRIGERATING APPARATUS

Don E. Dasher, Dayton, Ohio, assignor to General Motors Corporation, Dayton, Ohio, a corporation of Delaware

Application May 25, 1934, Serial No. 727,514
Renewed May 12, 1937

4 Claims. (Cl. 62—129)

This invention relates to refrigerating apparatus and more particularly to two temperature refrigerating systems.

Heretofore, household refrigerators and air conditioners employing but a single refrigerating system, have had evaporating means operating at a single evaporating temperature and pressure range. In these and other compression refrigerating systems, the pressure energy of the liquid refrigerant in flowing from the high side to the low side of the system, has not been used and has gone to waste.

It is an object of my invention to make use of this pressure energy to create other evaporating pressures for providing a more efficient refrigerating process and apparatus.

It is another object of my invention to provide an improved type of multiple temperature refrigerating system capable of maintaining a plurality of evaporating pressures without a loss of efficiency wherein only one suction line is required to connect the compressor with the evaporating means for withdrawing evaporated refrigerant.

It is a further object of my invention to provide an improved and more efficient refrigerating system for household refrigerators and air conditioners employing a plurality of evaporators operating at different evaporating pressures and temperatures and to provide an improved refrigerant control in which a controlled flow of liquid refrigerant is provided from one evaporator to another.

Further objects and advantages of the present invention will be apparent from the following description, reference being had to the accompanying drawings, wherein a preferred form of the present invention is clearly shown.

In the drawings:

Fig. 1 is a diagrammatic view of a two temperature household refrigerator and refrigerating system embodying my invention.

Fig. 2 is another diagrammatic view of a two temperature household refrigerator and refrigerating system embodying another form of my invention.

Fig. 3 is a diagrammatic view illustrating a two temperature air conditioning unit and refrigerating system embodying my invention; and

Fig. 4 is a diagrammatic view of a two temperature air conditioning and refrigerating system embodying another form of my invention.

Referring to the drawings, and more particularly to Fig. 1, there is shown diagrammatically an insulated refrigerator cabinet 20 having an

insulated freezing compartment 21 containing a freezing or low temperature evaporating means 22 and an insulated food storage compartment 23 containing a high temperature evaporator 24. The evaporators 22 and 24 are supplied with liquid refrigerant by a refrigerant liquefying apparatus including a compressor 25 for compressing the refrigerant and for pumping the compressed refrigerant into a condenser 26 where the compressed refrigerant is liquefied and collected in a receiver 27. From the receiver 27, the liquid refrigerant is forwarded through a supply conduit 28 under the control of a suitable control device such as a restrictor 29 which is provided with a nozzle 30 located within a Venturi tube 31.

The restrictor 29 and the nozzle 30 change the pressure energy of the liquid refrigerant into velocity energy and discharge a stream of liquid into the venturi at a high velocity. This forms a jet pump which pumps vapor from the suction chamber 32 of this jet Venturi means. The nozzle 30 may be moved parallel to the axis of the Venturi tube in order to vary the pumping effect of this jet. The liquid refrigerant discharged from the nozzle 30 of the jet pump flows into the high temperature evaporator 24.

When the high temperature evaporator 24 is filled with liquid refrigerant, the float valve 33 within the float chamber 34 is lifted to open the valve and permit the surplus liquid refrigerant to flow through the tubing 35 into the lower portion of the freezing evaporator 22. The liquid refrigerant within the freezing evaporator 22 evaporates and absorbs the heat from any water in the ice trays 36 and the ambient air within the freezing compartment and this evaporated refrigerant is removed through the tubing 37 connected to the suction chamber 32 of the jet pump which creates a substantially lower evaporating pressure in the freezing evaporator 22 than in the high temperature evaporator 24.

The liquid refrigerant within the high temperature evaporator 24 evaporates and absorbs heat from the ambient air within the food compartment 23 and this evaporated refrigerant is withdrawn from the top of the float chamber 34 through the return conduit 40 which is connected to the inlet of the compressor 25. The compressor 25 is driven by an electric motor 41 which is connected in series with the snap acting switches 42 and 43 which are connected in parallel electric circuit relation with each other and which are controlled respectively by the thermostatic bulb 44 located within the freezing com-

partment 21 and the thermostatic bulb 45 located within the food storage compartment 23. Thus, when refrigeration is required in either of these compartments, the compressor is caused to operate so as to supply refrigeration thereto. However, if desired, the switches 42 and 43 may be placed in series so that the refrigerating system will operate only when both of the compartments require refrigeration.

10 By employing the jet pump means operated by the pressure difference between the pressure of the liquid refrigerant in the receiver or high side of the refrigerating system and the pressure within the high temperature evaporator 24, a 15 substantially lower evaporating pressure and temperature is created within the freezing evaporator 22 than in the high temperature evaporator 24 without the use of additional energy. In addition to this gain in efficiency by the use of the 20 two evaporators, one for freezing purposes and one for cooling the food storage compartment, the high temperature evaporator 24 may operate at a much higher evaporating pressure and temperature than when only one evaporator operating 25 within a single pressure range is employed for both the freezing of ice cubes and comestibles, as well as for cooling the food storage compartment. This enables the compressor 25 to operate at a higher back pressure than customary 30 with household refrigerating systems employing but a single evaporator and this, of course, reduces the load upon the compressor 25 of the electric motor 41, because the pressure difference 35 between the refrigerant pressure on the inlet side of the compressor and that on the outlet side of the compressor is considerably less.

This system also permits the freezing evaporator to be operated at lower temperatures than is customary where a single evaporator is employed 40 for both freezing and box cooling purposes. As a result of this, freezing can be done much more quickly in a refrigerator of this type than in those now commonly used. By operating the food storage compartment evaporator at a high temperature, which, of course, is below the desired 45 food compartment temperature, a relatively high humidity may be maintained within the food storage compartment 23 and dehydration of foods and particularly dehydration of vegetables may be avoided.

50 In Fig. 2, there is shown a two temperature household refrigerator 50 having an insulated freezing compartment 51 containing a freezing evaporator 52 and an insulated food storage compartment 53 separate from and insulated from the freezing compartment 51 and provided with a high temperature evaporator 54. Liquid refrigerant is supplied to the evaporators by a refrigerant liquefying apparatus including a compressor 55 for compressing the refrigerant and for forwarding the compressed refrigerant to a condenser 56 where the compressed refrigerant is liquefied and collected in a receiver 57. From the receiver 57, the liquid refrigerant is forwarded through a supply conduit 58 under the control of a suitable control device, such as a restrictor 59, which controls the flow of liquid refrigerant into the high temperature evaporator 54.

70 As in the form shown in Fig. 1, the outlet of the high temperature evaporator 54 is provided with a float valve 60 within the float chamber 61 which permits the surplus of liquid refrigerant from the high temperature evaporator to flow 75 through the conduit 62 into the freezing evapora-

tor 52. The liquid refrigerant within the high temperature evaporator 54 evaporates and absorbs heat from the air within the food storage compartment 53 and this evaporated refrigerant is conducted from the top of the float chamber 61 by the return conduit 63 to the crank case 64 of the compressor 55. The liquid refrigerant within the freezing evaporator 52 evaporates and absorbs heat from the ice trays 65 and this evaporated refrigerant is conducted through a second 10 return conduit 66 to the inlet chamber 67 of the compressor 55.

The compressor 55 disclosed in Fig. 2 is of a suitable or conventional construction to provide a so-called multiple effect compressor. In other 15 words, when compressor 55 is operated it withdraws a certain amount of gaseous refrigerant from each of the evaporators of the system and forces the combined withdrawn charge of gaseous refrigerant under pressure into the condenser 56. 20 Operation of the multiple effect compressor 55, therefore, causes refrigerant evaporated in evaporator 52 to be drawn through conduit 66, inlet chamber 67, and under control of a suitable inlet valve 68 into the compression chamber 69 provided between the cylinder head and the compressor piston 70. This withdrawing of evaporated refrigerant from evaporator 52 occurs during the down stroke of piston 70 and when the piston reaches its lowermost position of its down 30 stroke a passage 71, connecting the compressor crankcase 64 with the compression chamber 69, is uncovered. Evaporator 54 communicates, by way of conduit 63, with the interior of compressor crankcase 64, and since the refrigerant evaporated in evaporator 54 is of higher pressure than refrigerant evaporated in evaporator 52 this high pressure refrigerant vapor flows, when piston 70 uncovers passage 71, from the compressor crankcase 64, through passage 71, into the compression 40 chamber 69. Upon each down stroke of piston 70, the chamber 69 is thus filled with gaseous refrigerant comprising a mixture of refrigerant evaporated from each evaporator 52 and 54 and which mixture is of a pressure corresponding to 45 the evaporating pressure of the high temperature evaporator 54. By substantially simultaneously withdrawing evaporated refrigerant from each evaporator 52 and 54 a high volumetric efficiency is insured for the multiple effect compressor 55. 50 The combined charge or mixture of gaseous refrigerant so drawn into the compression chamber 69 is compressed by the up stroke of piston 70 of compressor 55 and flows through a suitable pressure actuated outlet valve 72 into condenser 56 55 where it is cooled and liquefied.

A similar electrical system is provided for this refrigerating system including the compressor motor 73 for driving the multiple effect compressor which motor is in series with the snap acting 60 switches 74 and 75 which are placed in parallel circuit relation with each other and which are operated by thermostatic bulbs 76 and 77 located in the freezing and food compartments respectively. In this modification the same form of 65 liquid refrigerant control is employed but a different type of pumping means is employed for creating the pressure differences between the freezing evaporator and the high temperature evaporator.

70 In Fig. 3 there is an air conditioning system embodying my invention including a high temperature evaporating means 80 adapted to contain liquid refrigerant and a low temperature evaporating means 81 also adapted to contain liquid 75

refrigerant. These evaporators 80 and 81 are located within an air conditioning unit 82 which is provided with a centrifugal fan 83 driven by an electric motor 84 which circulates or discharges the fluid medium to be cooled, namely: air, upwardly, first over the surfaces of the high temperature evaporator 80 and then over the surfaces of the low temperature evaporator 81 after which the air is discharged through the screen or grille work 85 in the top of the air conditioning unit 82 which distributes the cooled air into the room.

The evaporating means is supplied with liquid refrigerant by a refrigerant liquefying apparatus 86 which is preferably located outside of the room or space to be cooled or which has its heat removed from the room in some suitable manner. This refrigerant liquefying apparatus 86 includes a compressor 87 for compressing the refrigerant and for forwarding the compressed refrigerant to a condenser 88 where the compressed refrigerant liquefies under the influence of pressure and cooling. This liquid refrigerant is cooled in a receiver 89 and forwarded through a supply conduit 90 under the control of a thermostatic valve 91 to a restrictor or other suitable control means 92 which, together with the nozzle 93 changes the pressure energy of the liquid refrigerant into velocity energy within the venturi 94 of a jet pump 95 which has an inlet or suction chamber 95. The liquid refrigerant discharged from the nozzle 93 flows into the high temperature evaporator 80 and cools the air flowing over its surfaces a certain amount which is insufficient to properly cool the air in the room. This evaporated refrigerant is returned to the compressor through the return conduit 96.

Liquid refrigerant is supplied from the lower portion of the high temperature evaporator 80 through a conduit 97 under the control of a thermostatic valve 98 to the low temperature evaporator 81 where the evaporation of the liquid refrigerant further cools the air which is circulated through the air conditioning unit, so that the air will finally be discharged at the desired discharge temperature. The refrigerant which evaporates in the low temperature evaporator 81 is withdrawn through the conduit 99 which is connected to the suction chamber 95 of the jet pump for this purpose. The thermostatic valve 91 is controlled by a thermostatic bulb 100 in heat exchange relation with the return line 96 so as to stop the supply of liquid refrigerant when liquid refrigerant enters the return conduit 96. Likewise, the thermostatic bulb 101 is placed in heat exchange relation with the conduit 99 so as to close the thermostatic valve 98 when any liquid refrigerant reaches that portion of the conduit 99.

The compressor 87 is driven by an electric motor 102 under the control of a snap acting switch 103 controlled by a thermostatic bulb 104 located within the air in the room or space to be cooled. By the use of this system, the air may be cooled more efficiently by employing the jet pump which is operated by the pressure energy of the liquid refrigerant from the high pressure side of the system to create a lower evaporating pressure and temperature within the evaporator which finally cools the air to the desired temperature. In this way, the desired temperature differences between the air flowing over the evaporating surfaces and the temperature of the evaporated surfaces may be maintained so as to effect rapid heat transfer therebetween. By employing a plurality of evaporators and by employing the jet pump to create

a lower evaporating pressure and temperature in the final or low temperature evaporator, the system may operate at a higher back pressure than when only a single evaporating means operating at a single evaporating pressure range is employed. This enables the air conditioning to be done more efficiently and more economically.

In Fig. 4 there is shown an air conditioning unit 120 containing a high temperature evaporator 121 and a low temperature evaporator 122. An electrically driven fan 123 controlled by the switch 124 is provided for circulating the fluid medium to be cooled, namely: air, first over the surfaces of the high temperature evaporator 121 and then over the surfaces of the low temperature evaporator 122. After passing over these evaporating surfaces, the air flows through a grille or screen 125 at the top of the unit 120 from which it is discharged into the air in the room or space to be cooled. Liquid refrigerant is supplied to the evaporating means by a refrigerant liquefying apparatus 126 including a compressor 127 for compressing the refrigerant and for forwarding the compressed refrigerant to the condenser 128 where the compressed refrigerant is liquefied and cooled in a receiver 129. From the receiver 129, the liquid refrigerant is forwarded through a supply conduit 130 under the control of a suitable expansion control device such as a restrictor 131 which controls the supply of liquid refrigerant to the high temperature evaporator 121.

The outlet of the high temperature evaporator 121 is provided with a float chamber 132, containing a float control valve 133 which permits the evaporated refrigerant to return through the return conduit 134 to the crank case 135 of the compressor 127 while any surplus liquid refrigerant is permitted to flow through the conduit 136 to the low temperature evaporator 122. The refrigerant evaporates within the low temperature evaporator 122 and cools the air to the desired discharge temperature after the air has been pre-cooled by the high temperature evaporator 121. The evaporated refrigerant from the low temperature evaporator is returned to the inlet chamber 138 of the compressor 121 through a return conduit 139.

The compressor 127 in Fig. 4 is similar to the compressor disclosed in the system shown in Fig. 2 in that it is of a construction to produce a multiple effect. The multiple effect compressor 127 includes a piston 140 which has a port 143, covered by a valve 148, extending therethrough. During operation of the compressor 127 and when the piston 140 thereof moves downwardly refrigerant evaporated in the low temperature evaporator 122 is caused to flow through conduit 139, chamber 138 and past a valve 142 into the compression chamber 141. The compressor piston 140 upon reaching the bottom of its down stroke moves the port 143 provided therein below the cylinder wall and into communication with the crankcase 135. Refrigerant evaporated in the high pressure evaporator 121 then flows through conduit 134, crankcase 135, port 143 and past the valve 148 into the compression chamber 141. Thus the charge of gaseous refrigerant entering the compression chamber 141 upon each down stroke of piston 140 includes a mixture of refrigerant evaporated from each evaporator 121 and 122. This charge of refrigerant substantially simultaneously withdrawn from each evaporator is compressed upon the up stroke of piston 140 and flows under pressure through a suitable outlet check valve into the condenser 128 where it

is cooled in any well-known or conventional manner and liquefied. It is to be understood that, while I have disclosed multiple effect compressors for the systems shown in Figs. 2 and 4 of certain construction, other compressor structures capable of producing a multiple effect may be employed without departing from the spirit of the invention.

The compressor 127 is driven by an electric motor 145 which is controlled by a snap acting switch operated by a thermostat 147 located within the air in the room or space to be cooled. In this system, I have employed a similar liquid control for supplying liquid refrigerant to the low temperature evaporator and have employed a high temperature and a low temperature evaporator in order to secure a high average back pressure and higher capacity, efficiency, and economy for air conditioning systems. In such an air conditioning system the low temperature evaporator may operate at substantially the normal back pressure for single evaporator air conditioning means while the high temperature evaporator may operate at a higher back pressure to reduce the power requirements.

The restrictors 29, 59, 92 and 131 employed in the various systems disclosed are preferably of tubular form of a predetermined length and having a small bore or passage therethrough. However, restrictors of the type suitable for use in the systems disclosed are well-known to those skilled in the art and it is to be understood that I may employ other conventional restrictors such as valves, etc., without departing from the invention. Since the various systems disclosed are only diagrammatically shown it is also to be understood that the jet Venturi means employed therein may be positioned wherever desired or practicable to carry out the functions of the systems as described. For example, the jet Venturi means may be located on or above the normal liquid refrigerant level maintained in the evaporator into which the Venturi means discharges liquid refrigerant.

While the form of embodiment of the invention as herein disclosed, constitutes a preferred form, it is to be understood that other forms might be adopted, all coming within the scope of the claims which follow.

What is claimed is as follows:

1. Refrigerating apparatus including a condenser and a plurality of evaporators, a compressor for pumping refrigerant from the evaporators to the condenser and creating a higher pressure in the condenser than in the evaporators, said refrigerant being liquefied in the condenser, means for conducting and controlling the flow of liquid refrigerant from the condenser to one of the said evaporators, means for supplying liquid refrigerant from said one evaporator to another of said plurality of evaporators, said conducting and controlling means including pumping means energized by the pressure energy of the liquid refrigerant for creating a substantially lower evaporating pressure in one of

the evaporators than in another, and means for circulating a fluid medium first over one of the evaporators having a higher evaporating pressure and then over one evaporator having a lower evaporating pressure.

2. The process of refrigeration which comprises withdrawing evaporated refrigerant from an evaporating space, compressing the evaporated refrigerant and cooling the compressed evaporated refrigerant to liquefy the refrigerant, converting the pressure energy of the liquefied refrigerant into velocity energy, utilizing the velocity energy of the liquefied refrigerant to withdraw evaporated refrigerant from a second evaporating space to create a lower pressure in the second evaporator space than in the first mentioned evaporator space, discharging the liquefied refrigerant into the first mentioned evaporating space, conducting liquid refrigerant from said first mentioned evaporating space into the second evaporating space, and passing a fluid medium to be cooled into heat exchange relation first with the first mentioned evaporating space and then into heat exchange relation with the second evaporating space.

3. Refrigerating apparatus including a low temperature and a high temperature evaporator, a condenser and a compressor for pumping evaporated refrigerant from one of said evaporators into the condenser and creating a higher pressure within the condenser, said refrigerant being liquefied in the condenser, means for conducting and controlling the flow of liquid refrigerant to said evaporators, said means including separate means for restricting the flow of liquid to the low temperature evaporator, said conducting and controlling means including pumping means energized by the pressure energy of the liquid refrigerant for creating with the aid of the separate restricting means a lower evaporating pressure within the low temperature evaporator than in the high temperature evaporator, and means for directing the circulation of a fluid medium to be cooled first in heat exchange relation with the high temperature evaporator and thereafter in heat exchange relation with the low temperature evaporator.

4. Refrigerating apparatus including a plurality of evaporators, means for supplying liquid refrigerant to and for withdrawing gaseous refrigerant from said evaporators, means for conducting liquid refrigerant pre-cooled in one of said evaporators therefrom and controlling its entrance into another of said evaporators, means utilizing the energy of refrigerant flowing from said supply means to said one of said evaporators for creating a substantially lower evaporating pressure within said another evaporator than in said one evaporator, and means for directing the circulation of a fluid medium to be cooled first into heat exchange relation with said one evaporator and thereafter into heat exchange relation with said another evaporator.
